(57) **CLAIM**

The ornamental design for a table, as shown and described.

DESCRIPTION

FIG. 1 is a perspective view of a first embodiment of a table showing my new design;

FIG. 2 is a rear elevational view thereof, and the front elevational view is identical to the rear elevational view;

FIG. 3 is a left side elevational view thereof, and the right side elevational view is identical to the left side elevational view;

FIG. 4 is a top plan view thereof;

FIG. 5 is a bottom plan view thereof;

FIG. 6 is a perspective view of a second embodiment of a table showing my new design;

FIG. 7 is a rear elevational view thereof, and the front elevational view is identical to the rear elevational view;

FIG. 8 is a left side elevational view thereof, and the right side elevational view is identical to the left side elevational view;

FIG. 9 is a top plan view thereof;

FIG. 10 is a partial enlarged top plan view thereof; and,

FIG. 11 is a bottom plan view thereof.

Portions of the views shown in phantom form no part of the invention.
